UNITED STATES PATENT OFFICE.

DAVID O. ROYSTER, OF ST. LOUIS, MISSOURI.

AIR-COMPRESSOR.

1,293,204.

Specification of Letters Patent.

Patented Feb. 4, 1919.

Application filed January 23, 1915. Serial No. 3,878.

To all whom it may concern:

Be it known that I, DAVID O. ROYSTER, a citizen of the United States, residing at St. Louis, State of Missouri, have invented certain new and useful Improvements in Air-Compressors, of which the following is a specification.

My invention relates to new and useful improvements in air compressors of that type which employs two or more cylinders and being electrically driven.

The principal objects of my invention are, first to provide an air compressor which is composed of comparatively few parts, thereby materially reducing the liability of the device getting out of order; to provide a pump which can be cheaply manufactured and economically operated; to combine with the pump a small electric motor; to provide simple automatically operating means which is controlled by the pressure produced by the pump for cutting out the motor; and further to provide simple means for effecting a lubrication of the pistons.

With the foregoing and other objects in view, my invention consists in certain novel features of construction and arrangement of parts, hereinafter more fully described, claimed and shown in the accompanying drawings, in which—

Figure 1 is a side elevational view of a compressor of my improved construction with parts thereof in vertical section.

Fig. 2 is a front elevational view of the compressor.

Fig. 3 is a vertical section taken through the center of the check valves which control the inlet and outlet of air to and from the cylinders.

Fig. 4 is a vertical section of one of the pistons and showing the means utilized for delivering oil to the surface thereof.

Referring by numerals to the accompanying drawings, 1 designates a plate, preferably of cast metal, and formed integral therewith is a series of depending posts 2, the lower ends of which carry a horizontally disposed plate 3, the same being adapted to be attached to an air tank or reservoir 4.

Formed integral with and projecting upwardly from plate 1 is a standard 5, the same being provided at its upper end with a horizontally disposed bearing 6 in which is mounted for rotation a shaft 7. Fixed on

one end of this shaft is a gear wheel 8 and 55 fixed on the opposite end thereof is a disk 9.

Formed integral with the plate 1 near the ends thereof are vertically disposed cylinders 10, open at their upper ends, and mounted for operation in said cylinders are 60 pistons 11, same being provided with suitable packing rings 12. These pistons are provided with pockets 13 in their upper portions, which pockets are adapted to contain oil and positioned transversely in each piston 65 is a pin 14 in the end portions of which are formed passage ways 15 which establish communication from the pocket 13 to the external surface of the piston, thereby permitting oil to flow from said pocket to the 70 bearing surface of the piston.

Loosely mounted on the central portions of the pins 15 are connecting rods 16, the upper ends of which are journaled on wrist pins 17, which latter are carried by gear 75 wheel 8 and disk 9.

Mounted on plate 1 is a small motor 18, the shaft of which is provided with a pinion 19 which meshes with the teeth of gear wheel 8. An ordinary electric switch 20 is 80 fixed on a part of the standard 5 and said switch is connected to the lines leading to the motor.

The means of automatically operating this switch and which is controlled by the 85 pressure created by the pump comprises a housing 21 which is located on plate 1 and positioned in said housing is a flexible diaphragm 22. Positioned on top of said diaphragm is a plate 23 carrying an upwardly 90 projecting pin 24 which operates through the upper portion of housing 21 and located on the upper portion of said pin is a compression spring 25. The upper end of this spring bears against the lower end of a 95 cylindrical nut 26 the same being screw-seated in the upper end of housing 21 and which nut when manipulated increases or decreases tension offered by the spring.

The upper end of pin 23 is pivotally connected to a lever 27, the same being fulcrumed at 28 to the upright 5 and the opposite end of said lever being bifurcated to form a pair of fingers 29 which straddle the switch 20 and are adapted to engage the 100 push pins thereof.

Extending upward from the center of plate 3 and the point where the same con-

nects with the tongue 4 is a pipe 30 which is connected to a horizontal pipe 31, one end of which is connected by a vertically disposed pipe 32, to the lower end of housing 21. The opposite end of this pipe 31 is connected to an ordinary pressure reducing valve 33, the same being provided with a regulating nut 34, and leading from this valve 33 is a short pipe 35, the same being provided with an ordinary cut-off valve 36. This pipe 35 is the service pipe to which connection is made when it is desired to use the compressed air.

Connected to pipe 35 and leading upwardly through plate 1 is a pipe 37 to which is connected a gage 38 by means of which the pressure of the air being used can be readily ascertained.

The check valves for controlling the inlet and outlet of air to and from the cylinders 10 are each formed with a short vertically disposed cylindrical body 39 from the lower end of which projects a tubular extension 40, the same being screw-seated in the lower end of one of the cylinders 10. Formed in this housing 39 is a valve seat 41 on top of which operates a check valve 42.

The upper end of housing 39 is closed by a screw plug 43 and leading from the chamber within housing 39 above valve 42 is a tubular nipple 44 to which is connected the upper end of a tube 45, which latter leads downwardly and is connected to tank 4.

Screw seated in the lower end of housing 39 is the upper end of a tubular elbow 46, the same being provided at its upper end with a valve seat 47 on top of which is positioned a check valve 48.

The air drawn to the cylinder 10 enters through tubular elbow 46 and passes check valve 48 as it enters chamber within housing 39.

The operation of my improved compressor is as follows:

Current supplied to motor 18 enters same and pinion 19 engaging with gear wheel 8 drives shaft 7. The rods 16 are connected to gear wheel 8 and disk 9 and by reason of such connection pistons 11 are reciprocated within cylinders 10.

On the up-stroke of the piston air is drawn in through corresponding tubular elbow 46, past inlet check valve 48 through tubular connection 40 into the lower portion of cylinder 10.

On the down-stroke of the piston the air thus drawn into cylinder is forced out through tubular connection 40, past check valve 42, from thence through tubular connection 44 and tube 45 into tank 4. Nut 26 is manipulated to regulate the tension of spring 25, thus controlling the degree of pressure required to raise diaphragm 22, and when the pressure within tank 4 exceeds the maximum point for which the

regulator is set, diaphragm 22 will be forced upwardly, thereby forcing upward plate 23 and pin 24, and consequently swinging lever 27 on its fulcrum. This action shifts the position of fingers 29 and throws switch 20, thereby cutting off current to motor 18 and the automatic stops.

The pressure in tank 4 is reduced to working pressure in passing through reducing valve 33 and the desired pressure is taken from pipe 35 to the point of use.

A supply of oil is maintained in pocket 13 and while the pump is in operation the bearing surfaces between the piston and cylinder are effectually lubricated. Cap 43 and tubular elbow 46 may be readily removed to adjust or renew check valves 42 and 48.

It will be understood that when pressure in tank 4 lowers sufficiently to permit spring 25 to move diaphragm 22 downward lever 27 will be actuated to throw in switch 20, thereby supplying the motor with current and automatically starting the pump.

If desired, a housing either wholly or partially transparent may be positioned on plate 41 over the operating mechanism positioned on said plate, and which housing is shown in dotted lines in Fig. 2.

An air compressor of my improved construction is comparatively simple, can be easily and cheaply manufactured, will not readily get out of order, is economical in point of power used in operation, and the operation of said compressor is entirely automatic and controlled by the degree of pressure pumped up within the cylinder or container to which said compressor is connected.

It will be readily understood that minor changes in the size, form and construction of the various parts of my improved compressor can be made and substituted for those herein shown and described, without departing from the spirit of my invention, the scope of which is set forth in the appended claim.

I claim:

The combination with a reservoir of a member adapted to be directly connected to said reservoir, posts projecting upwardly from said member, a plate carried by said posts, a pair of cylinders formed integral with said plate, said cylinders being spaced apart and projecting above and below the plate, a bracket integral with said plate and projecting upwardly therefrom between the cylinders, a bearing formed in the upper end of said bracket, a shaft journaled in the said bearing, a gear wheel on one end of said shaft, a disk on the other end of said shaft, pistons operating within the cylinders, piston rods connected to said pistons and the gear wheel and disk, an electric motor mounted on the plate to one side of the

bracket, a pinion carried by the motor shaft, which pinion meshes with the gear wheel, a separate inlet and outlet check valve for controlling the passage of air to and from each cylinder, and a connection from each outlet check valve to the receptacle to which the compressor is applied.

In testimony whereof I hereunto affix my signature in the presence of two witnesses, this 21st day of January, 1915.

DAVID O. ROYSTER.
